UNITED STATES PATENT OFFICE.

OSCAR M. GODFREY, OF NORTH ANDOVER, MASSACHUSETTS, ASSIGNOR TO DAVIS & FURBER MACHINE COMPANY, OF NORTH ANDOVER, MASSACHUSETTS, A CORPORATION OF MASSACHUSETTS.

MACHINE FOR PICKING AND BURRING WOOL, ETC.

Application filed February 1, 1923. Serial No. 616,879.

To all whom it may concern:

Be it known that I, OSCAR M. GODFREY, a citizen of the United States, and a resident of North Andover, county of Essex, State of Massachusetts, have invented an Improvement in Machines for Picking and Burring Wool, Etc., of which the following description, in connection with the accompanying drawing, is a specification, like characters on the drawing representing like parts.

This invention relates to a machine for picking and burring wool and similar fibres acting to straighten out the fibres and remove therefrom the dirt, burrs and foreign substances associated therewith.

The object of the invention is to provide an improved means for insuring the removal of the burrs and preventing waste of fibres.

20 The object of the invention is more particularly to provide in combination with such a machine a rotary brush and guard plate so positioned and arranged as to re-pass through the burring operation burrs knocked out and carrying fibre.

These and other objects and features of the invention will appear more fully from the accompanying description and drawings and will be particularly pointed out in the 30 claims.

In the drawings;

Figure 1 illustrates diagrammatically in general side elevation a familiar type of picking and burring machine having embodied therein a preferred form of the present invention;

40 Figure 2 is a side elevation partially in vertical cross section showing in detail that portion of the machine embodying a preferred form of the invention;

Fig. 3 is a detail in side elevation and vertical cross section showing one of the adjustable supports for the brush.

The present invention is herein shown embodied in a machine for picking and burring wool or similar fibres of a well known and familiar type and as the invention relates to but one, although an important, step or feature of the burring operation it is necessary only to illustrate and describe in detail those parts of the machine particularly concerned with the present invention. Figure 1 shows the entire machine in a dia-

grammatic form and it will be recognized by those skilled in the art as of a familiar type. Such a machine in general comprises a frame and casing 1 enclosing all the working parts. At the admission end of the machine an endless conveyor 2 is mounted and driven. The mass of wool or other fibre is deposited on this conveyor and carried thereby into the bite of a pair of feed and separating rolls 3. The fibre is taken from these rolls by the main beater cylinder revolving on the shaft 4 inside of a cylindrical cage. This beater cylinder usually comprises spider-like heads 5, partially shown in detail in Fig. 2, and on the periphery of these heads are usually mounted parallel spaced slats 6 carrying rows of teeth 7 projecting in the direction of rotation indicated by the arrows. These teeth seize the mass of fibre from the rolls 3. During the rotation of the beater cylinder the heavier dirt and foreign substances drop between the slats into the cage and fall out at the bottom while the lighter dirt and dust are sucked out from the cage by a suction fan 8 mounted at the top of the casing.

At the side of the beater cylinder opposite the feed is mounted a rotary burring cylinder 9. This cylinder rotates in a direction opposite to that of the main beater cylinder and is provided on its exterior with rows of teeth 10 pointing in the direction of rotation of the burring cylinder and generally formed in the periphery of parallel annular steel blades spaced throughout the length of the cylinder. The periphery of this burring cylinder is sufficiently close to the path travelled by the teeth 7 of the main beater cylinder to cause the fibres to be taken by the burring cylinder from the main beater cylinder and to lie in a bat on the peripheral surface of the burring cylinder.

A rotary burr guard 11 is mounted peripherally adjacent, and usually beneath, the burring cylinder 9. This burr guard is provided on its periphery with radially projecting steel blades 12. The burr guard rotates at a high speed and in the opposite direction to the burring cylinder. Its function is to knock off the burrs and foreign substances lying on the periphery of the burring cylinder while the fibres remain held in the teeth of the burring cylinder.

The burr guard shaft is mounted at its ends in bearing blocks vertically and laterally adjustable in the frame.

The bat of fibre is usually put through one or more subsequent burring operations. In the machine illustrated a second burring cylinder 13 of similar construction to the burring cylinder 9 is mounted with its periphery adjacent thereto and revolving in the opposite direction so that the bat of fibre is transferred from the burring cylinder 9 to the burring cylinder 13. A second rotary burr guard 14 is mounted adjacent the burring cylinder 13 and acts in a similar manner to the burr guard 11. The bat of fibre is removed from the final burring cylinder and discharged from the machine usually by a rotary brush 15 revolving in a direction opposite to that of the last burring cylinder.

When the burrs are knocked out from the bat of fibre by the burr guards, and particularly in the case of the burr guard such as 11 first acting upon the fibre, they frequently carry with them more or less fibre which is wasted or requires a separate operation for its removal. The present invention acts to permit such burrs if free from fibre, to drop out of the machine but, if carrying fibre, acts to repass them through the burring operation so as insure the saving of this fibre.

While the invention may be applied to any or all of the pairs of co-operating burring cylinders and burr guards it is especially useful in connection with the burring cylinder and burr guard first acting upon the fibre after it passes from the main beater cylinder and it is consequently illustrated in the preferred form in this position. While terms such as "upper" and "lower" and similar terms are herein used for convenience they are to be understood as indicating the relationship of the elements and not as restrictive.

In the preferred embodiment of the invention a cylindrical rotary brush 16 is mounted in the angle between the main beater cylinder and the burring cylinder 9. This brush is preferably formed as illustrated of tufts of bristles so that its periphery presents a substantially continuous surface of bristle points. The periphery of this brush is so positioned that it is sufficiently adjacent to the toothed periphery of the burring cylinder 9 as to press the fibres between the teeth of the burring cylinder leaving the burrs and foreign substances on the surface. The periphery of the brush is also so positioned that the teeth 7 of the main beater cylinder in their travel past the brush may seize burrs carrying fibre and hold on the surface of the brush. The periphery of this brush rotates at a slower speed than but in the same direction as the toothed periphery of the burring cylinder.

The position of the rotary brush 16 to secure the desired results is preferably secured by making the bearings carrying the shaft 17 of the brush adjustable in two directions herein shown as first in a direction radially of the beater cylinder and second in a direction transversely of the plane of the radial adjustment so that as a result the brush is adjustable toward and from the peripheries of both the main beater cylinder and the burring cylinder. The adjustment of one of the bearing blocks 18 for the shaft 17 is shown in Figure 3. The bearing block 18 is there shown mounted on a bracket 19 by means of a bolt 20 passing through a vertical slot in the vertical arm 21 of the bracket. The opposite end of the block 18 is provided with a set screw 22 threaded therethrough and abutting a flat surface 23 on the frame 1. Thus by loosening the bolt 20 and adjusting the set screw 22 the bearing block may be raised and lowered with respect to the surface 23. This surface is shown as extending radially of the main beater cylinder and the bracket 19 together with the lower end of the set screw 22 is slidable along this surface to give the desired radial adjustment. As a means for effecting the radial adjustment a set screw 24 is shown threaded into the bracket 19 and journaled in a bracket 25 secured by a bolt 26 to the frame.

It will now be seen that the burr guard 11 is mounted in the angle of diverging travel between the burring cylinder 9 and the brush 16 with its periphery rotating in the opposite direction to the burring cylinder, but in the same direction as the periphery of the brush.

A guard plate 27 extends between the brush 16 and the burr guard 11 and beneath the brush. This plate is curved as shown so as to conform throughout its lower portion to the periphery of the brush and is mounted at its ends on bases 28. These bases in turn are mounted on brackets 29 secured to the frame. The brackets 29 are vertically adjustable by means of the bolts 30 passing through slots in the frame and the bases 28 are horizontally adjustable on the brackets by means of bolts 31 passing through slots in the brackets. Thus the guard plate is adjustable to vary the distance between its upper edge and the periphery of the burring cylinder and to vary the space between its bottom portion and the brush periphery.

An auxiliary guard plate 32 is mounted beneath the brush spaced from the main guard plate and is vertically adjustable toward and from the brush by means of the set screw 33 passing through a slot therein and into the frame.

The brush and the guard plates are so positioned, by means of the adjustments provided, that the burrs knocked off from the

10 fibre on the burring cylinder by the burr guard 11 are thrown over the top of the guard plate 27 and against the brush 16. Those burrs that are free from fibre slide down the curved surface of the guard plate and drop out through the bottom or through the opening provided between the main guard plate and the auxiliary guard plate 32. Those burrs that still carry fibre clinging to them are caught by the brush and, the guard being adjusted sufficiently close to the brush, are rolled around by the brush and in many cases the fibre is stripped from them by the brush so that they are freed from fibre and drop out at the bottom. 15 Those burrs which carry a larger quantity of fibre still cling to the brush and are carried around and repassed through the burring operation. With the brush located in the position shown in Fig. 2 such burrs and fibre are seized by the teeth of the main beater cylinder and carried around and transferred to the burring cylinder to go through the operation again. Thus it is 20 practically impossible for burrs to pass through the machine and be discharged therefrom carrying fibre and it is practically insured that the fibre shall be stripped or removed from the burrs.

25 The adjustment of the upper edge of the guard plate 27 toward and from the periphery of the burring cylinder depends upon the kind of the stock being acted upon. If the stock is light the guard plate 30 may be adjusted further away to prevent the fibre being carried down to the right of the guard while if the stock is heavy the guard plate is adjusted closer. The burr guard acts like a fan and if the stock were 35 too light the fibre would carry down to the right of the guard which would obviously be objectionable.

40 The brush as has been pointed out is preferably made of bristles so inserted as to give a continuous surface containing a very large number of pointed ends per square inch, a much larger number than is yet commercial in a wire brush, but the invention is not to be restricted to the particular kind of brush 45 so long as it performs the desired function.

Having thus described the invention what is claimed as new and desired to be secured by Letters Patent is:

50 1. A machine for picking and burring wool, etc., comprising a rotary main beater cylinder; a rotary burring cylinder rotating in the opposite direction to, peripherally adjacent, and acting to take the fibre from, the main cylinder; a cylindrical rotary brush mounted in the angle between the main beater and burring cylinders, peripherally adjacent, rotating at a slower speed than 55 and in the same direction as, and acting to press the wool fibres into the toothed periphery of, the burring cylinder; a rotary

burr guard mounted at the side of the brush opposite the main beater cylinder, rotating at a higher speed than and in the opposite direction to, and peripherally adjacent, the burring cylinder; and a guard plate extending between the brush and the burr guard and beneath the brush, and so positioned that the burrs knocked off the burring cylinder by the burr guard are thrown thereby over the top of the guard plate and, if free from fibre, slide down the guard plate and drop out at the bottom and, if carrying fibre, are caught by the brush and either stripped or taken from the brush by the main beater cylinder and 70 passed through the burring operation again. 75

2. A machine for picking and burring wool, etc., having the construction defined in claim 1, together with means for adjusting the brush toward and from the peripheries of the main beater cylinder and burring cylinder. 80 85

3. A machine for picking and burring wool, etc., having the construction defined in claim 1, together with means for adjusting the brush radially of the main beater cylinder and means for adjusting the brush transversely of the plane of its radial adjustment. 90

4. A machine for picking and burring wool, etc., having the construction defined in claim 1, together with means for adjusting the guard plate to vary the space between the bottom portion thereof and the brush periphery. 95

5. A machine for picking and burring wool, etc., having the construction defined in claim 1, together with means for adjusting the guard plate to vary the distance between its upper edge and the periphery of the burring cylinder. 100 105

6. A machine for picking and burring wool, etc., having the construction defined in claim 1, together with means for adjusting the guard plate to vary the distance between its upper edge and the periphery of the burring cylinder and to vary the space between its bottom portion and the brush periphery. 110

7. A machine for picking and burring wool, etc., having the construction defined in claim 1, together with an auxiliary guard plate mounted beneath the brush and spaced from the main guard plate, and means for adjusting the auxiliary guard plate toward and from the brush. 115

8. A machine for picking and burring wool, etc., comprising a rotary burring cylinder carrying on its periphery a bat of fibre during the burring operation; a cylindrical rotary brush mounted peripherally adjacent, rotating at a slower speed than and in the same direction as, and acting to press the wool fibres into the toothed periphery of, the burring cylinder; a rotary burr guard 120 125 130

mounted in the angle of diverging travel between the burring cylinder and brush, rotating at a higher speed than and in the opposite direction to, and peripherally adjacent, the burring cylinder; and a guard plate extending between the brush and the burr guard and beneath the brush and so positioned that the burrs knocked off the burring cylinder by the burr guard are thrown thereby over the top of the guard plate and, if free from fibre, slide along the guard plate and are discharged from the machine and, if carrying fibre, are caught by the brush and either stripped or taken from the brush and passed through the burring operation again.

9. A machine for picking and burring wool, etc., having the construction defined in claim 8, together with means for adjusting the brush toward and from the periphery of the burring cylinder.

10. A machine for picking and burring wool, etc., having the construction defined in claim 8, together with means for adjusting the guard plate to vary the distance between its upper edge and the periphery of the burring cylinder and to vary the space between its bottom portion and the brush periphery.

In testimony whereof, I have signed my name to this specification.

OSCAR M. GODFREY.
